Charles V. Gooding.

UNITED STATES PATENT OFFICE.

MAX C. ROSENFELD, OF BOSTON, MASSACHUSETTS.

TOOL FOR REMOVING AND ATTACHING BOTTLE-CAPS.

1,360,321.

Specification of Letters Patent. Patented Nov. 30, 1920.

Application filed October 10, 1919. Serial No. 329,753.

To all whom it may concern:

Be it known that I, MAX C. ROSENFELD, a citizen of the United States, residing at Boston, in the county of Suffolk and State of Massachusetts, have invented new and useful Improvements in Tools for Removing and Attaching Bottle-Caps, of which the following is a specification.

This invention relates to a tool particularly adapted to remove caps from bottles, the same being also adapted to apply caps to bottles.

The object of the invention is to provide a cheap and durable tool for the purpose specified.

The invention consists in a tool of the character described in the following specification and particularly of the form and construction set forth in the claims.

20 In the drawings:

Figure 1 is a side elevation, partly in section, of my improved tool showing the same in the position assumed thereby when applying a cap to a bottle.

25 Fig. 2 is a side elevation of said tool illustrating the same in position to remove a cap from a bottle.

Like numerals refer to like parts in the views of the drawings.

30 In the drawings, 5 is a tool constructed in accordance with my invention and consisting of a handle portion 6, a head 7 and a prong 8. The head 7 consists of a cylindrical portion 9 which is connected to the handle portion 6 by a conical portion 10. The prong 8 is located adjacent to the conical portion 10 and has a straight edge 11 which is preferably substantially parallel to the face of the conical portion 10 and is 35 separated from said conical portion by a space 12 which is substantially of the same width as the height of the bottle cap.

40 13 is the neck of a bottle and 15 the cap of well known style, formed of metal and 45 having a corrugated rim whereby the same may be sprung onto the neck of the bottle by pressure exerted on the bottle neck against said cap.

The tool is preferably provided with an 50 annular flange 16 at the opposite end thereof from that upon which the head 7 is located and said head is provided with a recess 17, the wall 18 of said recess being slightly conical in form. The outer end of the prong 55 8 terminates inside a straight line lying in the peripheries of said cylindrical portion 9 and the annular flange 16.

The tool hereinbefore specifically described is operated as follows: When a cap is being affixed to the bottle, said cap is 60 placed upon the end of the bottle neck, the tool is then placed as illustrated in Fig. 1, with the cap inclosed in the recess 17 and while the tool is being held in a vertical position with one hand, a blow is struck upon 65 the flanged end 16 with a hammer. This causes the bottle cap to be affixed to the bottle.

To remove the cap the holder is placed in the position illustrated in Fig. 2, with the 70 prong 8 projecting beneath the lower edge of the bottle cap and with the conical portion 10 of the head resting on the top of the cap. The bottle is held with one hand and the tool is held in the other hand. After 75 placing the tool in the position illustrated in Fig. 2 a slight upward movement upon the holder causes the cap to become detached from the bottle, and in this connection it will be seen that in removing the cap it is 80 firmly gripped and held in position between the head and the prong while being detached from the bottle neck.

Having thus described my invention, what I claim and desire to secure by Letters Patent is:

1. A bottle cap remover comprising a handle terminating adjacent to one end thereof in an enlarged conical portion and a prong 90 projecting laterally from said handle adjacent to said conical portion, with a space between said conical portion and prong substantially equal in width to the height of the cap which is to be removed, the edge of said prong adjacent to said conical portion 95 being substantially parallel thereto.

2. A bottle cap remover comprising a cylindrical portion at one end thereof, an annular flange at the opposite end thereof, a handle, an enlarged conical portion intermediate said cylindrical portion and said handle and a prong projecting laterally from said handle adjacent said conical portion, the outer end of said prong terminating inside a straight line lying in the peripheries of said cylindrical portion and said annular flange.

In testimony whereof I have hereunto set my hand in presence of two subscribing witnesses.

MAX C. ROSENFELD.

Witnesses:

FRANKLIN E. LOW,
CHARLES L. GOODING.
